(57) **CLAIM**

The ornamental design for a closure for containers, as shown and described.

DESCRIPTION

FIG. 1 is a top, front, and right side perspective view of a closure for containers, with the covers in the closed configuration, according to the present invention;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a rear view thereof;

FIG. 8 is an exploded, top, front, and left side perspective view thereof, with the removable tab portion shown in the removed configuration;

FIG. 9 is a top, front, and left side perspective view thereof, in an alternate position with the covers in the opened configuration;

FIG. 10 is a top, front, and right side perspective view thereof, in an alternate position with the covers in the opened configuration; and,

FIG. 11 is a bottom, rear, and right side perspective view thereof, in an alternate position with the covers in the opened configuration.

The broken lines depict portions of the closure for containers that form no part of the claimed design. In the views of the bottom, FIGS. 5 and 11, the innermost solid line forms the boundaries to the claim.
